US00D593553S

(12) **United States Design Patent**
Okamoto et al.

(10) **Patent No.:** **US D593,553 S**
(45) **Date of Patent:** **** Jun. 2, 2009**

(54) **ELECTRONIC BOOK**

(75) Inventors: **Tomoyuki Okamoto**, Kasugai (JP);
Koichi Kondo, Nissin (JP); **Mitsuo Hirota**, Toyoake (JP); **Sakiko Kobayashi**, Nagoya (JP)

(73) Assignee: **Brother Industries, Ltd.**, Nagoya (JP)

(**) Term: **14 Years**

(21) Appl. No.: **29/327,868**

(22) Filed: **Nov. 14, 2008**

(30) **Foreign Application Priority Data**

May 16, 2008 (JP) 2008-012256

(51) **LOC (9) Cl.** **14-02**

(52) **U.S. Cl.** **D14/341**

(58) **Field of Classification Search** ..... D14/496, D14/401, 435, 474, 483, 217, 137, 138, 160, D14/168, 203.1–203.8, 341–347, 138 R, D14/138 C, 138 G, 454, 439, 455, 456, 192, D14/239, 247, 315, 327, 331, 336, 338, 339, D14/374, 393, 394, 399, 400, 429, 432, 125, D14/126, 129, 130, 314; D21/324, 329, D21/330, 331, 333; D18/7; D10/32, 65; 455/556.1, 556.2, 11.1, 773, 344–347, 93, 455/95; 379/433.01, 433.07, 433.1, 433.11, 379/433.12, 433.13, 52; 345/169, 156, 173–179, 345/905; 348/14.02, 790; 341/22; 361/680; 273/148 B; 368/281; 715/727–729, 864; 370/342–344; 369/1, 2, 6, 12; 463/43–47

(57) **CLAIM**

The ornamental design for an electronic book, as shown and described.

DESCRIPTION

FIG. 1 is a top perspective view of an electronic book;

FIG. 2 is a bottom perspective view thereof;

FIG. 3 is a top view thereof;

FIG. 4 is a front view thereof;

FIG. 5 is a rear view thereof;

FIG. 6 is a right-side view thereof;

FIG. 7 is a left-side view thereof; and,

FIG. 8 is a bottom view thereof.
